US00D447068B1

(12) **United States Design Patent** (10) Patent No.: **US D447,068 S**
 Carlson et al. (45) Date of Patent: ** Aug. 28, 2001

(54) **RULER**

(75) Inventors: **Christopher Robert Carlson**, Wausau; **Cory R. Boudreau**, Madison; **David E. Barnard**, Madison; **Ryan W. Rindy**, Madison, all of WI (US)

(73) Assignee: **Alterra Holdings Corporation**, Tigard, OR (US)

(**) Term: **14 Years**

(21) Appl. No.: **29/131,746**

(22) Filed: **Oct. 27, 2000**

(51) LOC (7) Cl. **10-04**

(52) U.S. Cl. **D10/71**

(58) Field of Search D10/71; 33/483-494
